UNITED STATES PATENT OFFICE.

HARRY SOMERS, OF ARMSTRONG, BRITISH COLUMBIA, CANADA.

GATE-OPENING MEANS.

1,095,938.

Specification of Letters Patent.

Patented May 5, 1914.

Application filed September 15, 1913. Serial No. 739,955.

To all whom it may concern:

Be it known that I, HARRY SOMERS, a subject of the King of Great Britain, and a resident of Armstrong, Province of British Columbia, Dominion of Canada, have invented 5 a new and Improved Gate-Opening Means, of which the following is a full, clear, and exact description.

My invention relates particularly to the 10 operating means for road gates designed to be operated by a driver or equestrian to open the gate, and then for closing the same after having passed through the gate.

It is a design of the invention to improve 15 in various particulars devices of the character indicated, to the end that efficiency in operation may be promoted, as well as economy of manufacture and simplicity of adjustment and control.

20 The invention will be particularly explained in the specific description following.

Reference is to be had to the accompanying drawings forming a part of this specification, in which similar characters of reference indicate corresponding parts in all 25 the views.

Figure 1 is a perspective view of a gate-operating means embodying my invention; Fig. 2 is a plan view; Fig. 3 is a detail sectional side elevation showing the latch; and Fig. 4 is a detail plan view of the hinge 30 joint in the operating levers.

The invention is applicable to any swinging road gate 10 having a hinge post 11 and 35 latch post 12. To any suitable latch 13 are connected two latch cords 14, one at each side of the gate, each of said cords being carried to and connected with one arm of separate bell crank levers 15, the opposite 40 arms of said levers being connected respectively with pull ropes or other flexible elements 18, which are extended along the roadway above the gate, and at each side thereof, and connected with operating levers 19 fulcrumed as at 20 between the ends 45 on road posts 21. The pull ropes 18 extend from the respective levers 19 over sheaves 17, the pivot pins 22 of which constitute also the fulcrums of the bell crank 50 levers 15, and pass vertically through horizontal cross arms 16 suitably secured to the top of the gate 10. Thus the levers and sheaves 17 have common axes. The cross arms 16 comprise upper and lower plates 55 between which the levers 15 and sheaves 17 are received. The one rope 18 extends from

its lever 19 over the adjacent sheave 17 and across the top of the gate to a connection with the bell crank lever 15 at the opposite side, so that the two ropes overlap or cross, 60 the rope at one side of the gate being connected with the bell crank lever on the opposite side. A pull on one rope 18 will thus actuate the latch string at the opposite side of the gate to release the latch and permit the gate to swing. 65

A continuous rope or other flexible element 23 connects the two levers 19 at the ends opposite the connection with the pull ropes 18. The levers are provided with 70 handles 24 hinged as at 25 to the bodies of the levers. The hinge of each lever handle is provided with a spring 26, which normally tends to maintain the handle disposed vertically and thus normally the handle 75 will not overhang the roadway to afford an obstruction, but may be pulled downward by the operator to a position shown at the left of Fig. 1, for throwing the lever. A pull on either lever, it will be seen, will slacken the rope 18 connected with said lever and will exert a pull on the rope 23 connecting the levers, so that the opposite lever will exert a pull on its rope 14 and release the latch. The continued movements of the 80 levers will swing the gate toward the said opposite lever and away from the operator. 85

Additional latch posts 27 are arranged along the road at a distance to engage the latch when the gate is swung in either direction, said posts being provided with any suitable catch 28, according to the character of the gate latch 13. In the present instance the gate latch has an axially sliding spindle 29 extending through the adjacent 90 vertical member of the gate 10, and is connected with the resilient plate 30 secured to the gate, the arrangement being such that a pull on the latch will withdraw the resilient plate 30 from the catch 31 on the latch post 100 12. The rope 23 connecting the two levers runs over a pulley 32 on the hinge posts 11 and forms a direct, straight connection between the two levers. 95

Having thus described my invention, I 105 claim as new, and desire to secure by Letters Patent:

1. The combination with a swinging gate and its latch, of latch-tripping and gate-operating means comprising a pair of horizontal bell crank levers mounted on the gate, 110 one lever at each side, a sheave adjacent to

each lever, one sheave being beneath the lever adjacent thereto and one above its adjacent lever, pins constituting the fulcrum of the levers, the sheaves being held by and turning on said pins, latch strings connected at one end with the gate latch, each latch string at the opposite end being connected with one arm of one of said levers, flexible elements connected at one end with the opposite arms of said levers, gate operating levers mounted at opposite sides of the gate, a distance therefrom, an element connecting the gate-operating levers, said levers being connected also with the ends of the flexible elements opposite the latch levers, that flexible element connected with the latch lever at one side of the gate crossing over the gate to the opposite side and being connected with the gate operating lever of said opposite side.

2. The combination with a swinging gate, and its latch, of latch-tripping and gate-operating means comprising a pair of latch-operating levers of the first order mounted

on the gate, one at each side thereof, latch strings at each side of the gate, each connected with one end of the gate latch, and connected with one arm of that latch lever at the adjacent side of the gate, flexible elements connected at one end with the opposite arms of said levers, gate operating levers mounted at opposite sides of the gate, a distance therefrom, an element connecting the gate-operating levers, said levers being connected also with the ends of the flexible elements opposite the latch levers, that flexible element connected with the latch lever at one side of the gate crossing over the gate to the opposite side and being connected with the gate-operating lever on said opposite side.

In testimony whereof I have signed my name to this specification in the presence of two subscribing witnesses.

HARRY SOMERS.
